(57) **CLAIM**

The ornamental design for a kitchen for aircraft, as shown and described.

DESCRIPTION

FIG. 1 is a perspective view of a kitchen for aircraft showing my new design;

FIG. 2 is a front elevational view thereof;

FIG. 3 is a top plan view thereof;

FIG. 4 is a left side elevational thereof;

FIG. 5 is a right side elevational view thereof;

FIG. 6 is a cross-sectional view taken along lines 6-6 of FIG. 2; and,

FIG. 7 is a cross-sectional view taken along lines 7-7 of FIG. 2.

The broken lines in the drawings illustrate portions of the kitchen for aircraft that form no part of the claimed design. Arrow and line indicators and their respective numbers 6-6, 7-7 in FIG. 2 are for reference purposes only and form no part of the claimed design.
